WORD-BUILDING GAME

Louis Grudin, New York, N. Y.

Application January 21, 1937, Serial No. 121,425

1 Claim. (Cl. 35—35)

This invention relates to word-building games wherein the letters of words are composed of playing pieces.

My invention resides in novel playing-pieces used for composing letters of the alphabet upon a playing board, and a novel correspondence of the color of a playing board with portions of the playing pieces.

An object of my invention is to provide a novel word-building game which is interesting and instructive, and which permits exercise of player skill.

Another object of my invention is to provide novel pieces, which may be used in various combinations to compose the letters of the alphabet and the numerals.

A further object of my invention is to reduce the component parts of all letters and numerals to conveniently uniform and interchangeable parts, thereby permitting interchangeable constructions of letters while at the same time facilitating selective manipulation in letter-building and word-building games.

A still further object of my invention is to provide novel dice used for selecting combinations of playing pieces to compose letters in a novel word-building game.

These and other objects of my invention will become apparent in the following description in connection with the drawing, in which:

Figure 1 illustrates a preferred embodiment of the novel playing-pieces.

Figure 2 illustrates the optical effect resulting from placing said pieces upon the playing board.

Figure 3 illustrates several letters composed with the novel playing-pieces.

The letters of the alphabet as well as the numerals are composed of combinations of the novel semi-circular pieces 10 and 11 illustrated in Figure 1. The diameter of the smaller piece 11 is one-half the diameter of the larger piece 10. Pieces 10 and 11 may be made of wood, metal composition, cardboard or the like, and are uniformly colored.

45 A line 12 is marked upon one side 13 of piece 10, adjacent to the diameter thereof. The width of line 12 corresponds to the width of the lines which are to be made upon the letters in a manner to be hereinafter described. The opposite surface 14 of piece 10 has a semi-circular marking 15 along the circular border of piece 10. The markings 12 and 15 on semi-circular piece 10 are preferably colored to contrast with the color of the background or surfaces 13 and 14. For example, if a blue background is used for the piece 10, lines 12 and 15 are preferably colored yellow.

The small semi-circular pieces 11 are marked and colored in a manner similar to pieces 10. 60 On one black side 16 has a straight white line 17

marked adjacent the diameter. The other side 18 has the circular marking 19 thereon, as illustrated in Figure 1. In my preferred embodiment, the thickness of the lines 12, 15, 17 and 19 are made equal, and correspond to the thickness of the lines composing the letters of the game.

A plurality of semi-circular pieces 10 and 11 are used to play the word-building game. The surface of the board upon which the game is played is colored the same as the surfaces of the pieces 10 and 11, namely black, in my preferred form. Figure 2 illustrates a corner of the play-board 20. When pieces 10 and 11 are placed upon board 20, only the contrastingly colored lines 12, 15, 17 and 19 will be readily visible. The black surfaces or background portions of pieces 10 and 11 will be substantially invisible, being non-distinguishable from the similarly colored play-board 20. Accordingly, the black outlines 21—22 and 23—24 of pieces 10 and 11, indicated in dotted line, will be substantially invisible to the players. Contrasting white lines 12, 15, 17 and 19 are clearly set out against the black background of board 20.

A plurality of the pieces 10 and 11 are used to play the word-building game according to my present invention. The letters of the alphabet are composed of combinations of pieces 10 and 11. For example, letter A is composed with two large pieces 25 and 26 and one small piece 27 as illustrated in Figure 3, the straight line markings of the members 25, 26 and 27 being used. The letter B is composed by using the straight line of one large piece 28, and the curved lines of two small pieces 29 and 30. Letter C is the curved marking of one large member 31. D is composed of one straight and one curved marking respectively of two large pieces 32 and 33. All the letters of the alphabet together with the numerals may be readily composed with the novel pieces 10 and 11 according to the following table:

Combination of pieces:	Complete alphabet and numerals	45
1 large	C, I; #1	
1 large and 1 small	G, P, L, J; #7	
1 large and 2 small	B, K, R, F, X, Z, U; #2, 5, 6, 9	50
1 large and 3 small	E	
2 large	T, D, V, O; #0	
2 large and 1 small	H, Q, A	
2 large and 2 small	M, W	
3 large	N	
3 small	S, Y; #4	55
2 small	I; #3	
4 small	#8	

As indicated in the chart, different alternative letters of the alphabet, or numerals may be com- 60

posed from a selected group or combination of pieces.

5 Although I have described a preferred embodiment of the novel playing pieces which are used in composing the individual letters for the word-building game, it is to be understood that modifications and variations may be readily devised which fall within the spirit and scope of my present invention.

10 I claim:

A game piece for use in letter building comprising a semi-circular element having opposed plane surfaces: one of said surfaces bearing a straight line marking of substantial width and of contrasting color to said element along its chord 5 forming edge; the other of its surfaces bearing a curved marking of substantial width and of contrasting color to said element along its arcuate edge.

LOUIS GRUDIN. 10
